UNITED STATES PATENT OFFICE

138,542

DESIGN FOR A COVER FOR TRASH CANS

Joseph H. Monson, Denver, Colo.

Application February 16, 1944, Serial No. 112,600

Term of patent 7 years

(Cl. D58—26)

To all whom it may concern:

Be it known that I, Joseph H. Monson, a citizen of the United States, residing in the city and county of Denver and State of Colorado, have invented a new, original, and ornamental Design for Cover for Trash Cans, of which the following is a specification, reference being had to the accompanying drawing, forming part thereof.

In the drawing:

Figure 1 is a side elevational view of a cover for trash cans showing my new design;

Figure 2 is a side elevational view thereof with cover rotated ninety degrees from the position shown in Figure 1;

Figure 3 is a top plan view thereof; and

Figure 4 is a section taken on lines 4—4, Figures 2 and 3.

I claim:

The ornamental design for a cover for trash cans, as shown.

JOSEPH H. MONSON.
